UNITED STATES PATENT OFFICE.

ROBERT S. BLAIR, OF STAMFORD, CONNECTICUT.

BOWLING-PIN CONSTRUCTION.

Application filed April 26, 1923. Serial No. 634,681.

This invention relates to the construction of bowling pins and devices of like character. One of the objects of the invention is to provide a construction of the above nature, 5 strong and durable and adapted to meet the conditions of practical use in a highly satisfactory manner. Another object is to provide such a construction capable of withstanding hard usage for a long period of 10 time without ill effects. Another object is to provide a practical and effective art whereby such articles may be manufactured conveniently and at low cost. Other objects will be in part obvious or in part pointed out 15 hereinafter.

The invention accordingly consists in the features of construction, combinations of elements, arrangements of parts and in the several steps and relation and order of each of 20 the same to one or more of the others, all as will be illustratively described herein, and the scope of the application of which will be indicated in the following claims.

In the accompanying drawing, in which is 25 shown one of the various possible embodiments of the mechanical features of this invention,

Figure 1 is a side elevation of a bowling pin the lower portion being cut away;

Figure 2 is a bottom view of the bowling pin at one stage of the process of manufacture;

Figure 3 is a diagrammatic view in section representing another step of the process; and

Figure 4 shows the bowling pin in a still further step of manufacture.

Referring now to the drawing in detail, there is shown a bowling pin having a main body portion 10 formed preferably of wood 40 and shaped to the desired contour of such devices in the usual manner, as by turning down the wood in a suitable lathe. It may be here noted that bowling pins in order to obtain the qualities most desired are generally made of a tough, resilient wood. In forming the pins they are carefully balanced and proportioned so that the center of gravity may fall at substantially the desired point and in order that they may stand 45 in an upright position with substantially the desired degree of stability. In order that the pins may retain their ability to thus stand erect and with the desired stability it is required that their bases be carefully leveled and thereafter be maintained in such 50 condition. The wooden pins are subjected to

extremely rough usage and without added protection their bases soon become dented and marred to such an extent that the pins are no longer capable of standing with the 60 stability that was originally intended. The provision of means for overcoming such difficulties without disturbing the balance and general substantial homogeneity of the bowling pins is an aim of this invention. 65

In Fig. 2 there is shown a bottom view of the wooden pin 10 and formed therein, as by turning, is an annular groove 11 preferably dove-tailed shape in cross section, as is seen more clearly in Fig. 3. Upon the groove 70 11 having thus been formed, the pin is inverted and a mold 12 is clamped about the lower portion thereof. Into the mold 12 through a suitable gate 13 therein is poured in a molten condition a suitable reinforcing 75 or protective material which upon hardening within the mold forms a surfacing or cap 14, as shown in Figs. 1 and 4, interlocked with the annular recess 13. The material 14 is preferably a metal alloy having a low melt- 80 ing point and a specific gravity as near as practicable to that of the wood of the pin 10, for example, an alloy of lead, 10; tin, 24; and bismuth, 66. The temperature of the molten alloy is not high enough to cause the 85 wood to char and, being of substantially low specific gravity, does not materially detract from the general homogeneity of the pin. In fact, the wood may be hollowed out as indicated at 10^a, if desired, to compensate for 90 the excess weight of the metal.

As is well known, with alloys of the above nature, they are not only fusible at a low temperature but, on solidifying, tend to expand instead of to contract, as do most metals 95 and alloys. This expansion increases the tightness of the joints and the security of attachment of the parts.

The inner wall 12^a of the mold 12 is preferably convex so that the cap or covering 14 is 100 formed with a central depression 14^a surrounded by an annular level surface 14^b. As is clearly shown in the drawings, a plug is fitted in the lower end of the cavity 10^a in order to prevent the entry thereinto of the 105 molten alloy and thus allow the cavity to compensate for the weight of the metal as above set forth. In order to true or level the bottom surface or base of the pin and thus insure its standing in the desired erect position, the pin is preferably suspended as by 110 a spring 15 and a plane horizontal heated

surface 16 is brought into contact with the surface 14^b. In this manner the alloy surface 14^b is fused slightly and the pin being suspended through its vertical center-line, 5 and the surface 16 being horizontal, the base surface of the pin will be molded so that it conforms to a plane substantially at right angles to its line of suspension. Thus the pin is provided with a base upon which it 10 will stand in a true erect position. The relatively hard and strong alloy will not easily become dented and marred but will retain its original conformation for a long period of time under the most severe use. The surfacing further serves to reinforce the wooden 15 portion of the pin against splitting.

From the above it will be seen that there are herein provided a device and art of making the same which embody the features of 20 this invention and attain the objects thereof.

As many possible embodiments may be made of the mechanical features of the above invention and as the art herein described might be varied in various parts, all without 25 departing from the scope of the invention, it is to be understood that all matter herein set forth or shown in the accompanying drawings is to be interpreted as illustrative and not in a limiting sense.

30 I claim as my invention:

1. The herein described art which consists in casting on the base of a bowling pin a protective material into interlocking relation therewith, said material consisting of a readily fusible alloy tending to expand on solidification.

2. The herein described art which consists in forming an annular recess in the lower portion of a bowling pin, pouring thereinto a 40 molten material in an amount to fill said recess and extend laterally beyond the walls thereof, and allowing said material to harden therein to form a reinforcement.

3. The herein described art which consists 45 in forming a recess in the base of a bowling pin, fitting a mold against the lower portion of said bowling pin the inner walls thereof being spaced from said base, pouring a mol-

ten material into said mold and said recess through the wall of said mold and toward the 50 pin, and permitting said material to harden therein forming a covering for said base interlocked with said recess.

4. The herein described art which consists in surfacing the base of a bowling pin with 55 a metal alloy of low melting point, suspending said bowling pin in an upright position, and applying a heated surface to said surfacing to level the same.

5. The herein described art which consists 60 in suspending a bowling pin and applying means to the base thereof to level the same.

6. The herein described art which consists in forming a recess in the bottom of a bowling 65 pin and forming on the bottom of said pin exterior to said recess a metallic protective member leaving said recess free from metal whereby the effect of the metal upon the center of gravity of the pin may be neutralized by the effect thereon of said recess.

7. The herein described art which consists in forming a recess in the bottom of a pin, forming a second recess in the bottom of the pin, and casting a metallic protective member 75 into said second recess, leaving said first recess unfilled.

8. The herein described art which consists in forming an annular recess in the lower portion of a bowling pin with undercut walls, 80 and casting into said recess molten metallic material and allowing said material to harden therein to form a reinforcement for the pin.

9. The herein described art which consists in forming a recess in the base of a bowling pin, mounting a mold upon the base of the pin, the central portion of the inner wall of which is nearer the pin than the outer portions, and casting a metallic reinforcement in 85 said mold into interlocking relation with said recess.

In testimony whereof, I have signed my name to this specification this 20th day of April, 1923.

ROBERT S. BLAIR.
